TOY

Walter J. Van Deest, Los Angeles, Calif.

Application November 6, 1933, Serial No. 696,842

2 Claims. (Cl. 273—58)

This invention relates generally to the class of games and toys, and is more particularly directed to those certain new and novel features which characterize a decidedly interesting and amusing form of play object and an important purpose of the invention is to provide an article of this nature from the use of which great amusement and considerable pleasure and healthful exercise may be had; one which will possess all of the ordinary functional qualities of a spherical or other customary form of ball, and to which will be contributed many added functional qualities and peculiarities by means of which the movements of the object will be very erratic and so uncertain as to make it practically impossible for one to appreciate or determine in advance the exact direction in which the object will move after it strikes the ground when thrown from the hands of a player.

5 A further object of the invention is to provide an article of the class described which is structurally designed so that same will tend to tumble over many uncertain paths rather than roll along a single straight path as would follow from the act of throwing a spherical ball.

10 With the above and other objects in view, which will appear as the description proceeds, the invention resides in the novel construction and arrangement of parts, all as will be more fully described hereinafter, illustrated in the drawing, and particularly pointed out in the claims.

15 Referring now to the accompanying drawing for a better understanding of the invention,

Figure 1 is a view in elevation of the toy;
35 Figure 2 is a section on the line 2—2 of Figure 1;

Figure 3 is a view looking into the side of the toy from a point at the arrow in Figure 1; and
40 Figure 4 is a plan view of one section of the cover member of the toy.

In carrying the invention into practice, I employ a body A which includes a cover member or casing 5 of flexible, but preferably inelastic, material. This cover member or casing 5 consists, 45 in the form herein illustrated, of four panels of two sections each, the sections themselves consisting of identical parts 6 and 7 sewed or otherwise suitably secured together at 8. Each of the parts 6 and 7 is characterized by a single piece of sheet material, cut to provide three equidistantly related dome or substantially cone-shaped projections 9. Connected straight lines drawn from vertex to vertex of these projections describe an equilateral triangle. These panels, 50 made up and sewed together as aforesigned, pro-

vide a complete enclosure for a rubber bladder 10 whose inflating stem 11 is accessible from beneath the laced flaps 12 so that the bladder may be inflated as desired.

Having described the essential characterizing features of the invention, I shall now describe additional novel features of the invention and the shape and form of the structure when the bladder 10 is inflated.

It follows that with the casing member 5 constructed as aforesaid, i. e., from four panels of two sections each, joined together as shown, or, in other words, four each of the parts 6 and 7, the complementary dome-shaped projections 9 of the respective parts 6 and 7 mutually define 15 semi-spherical or roundish protuberances which are disposed in co-axially aligned or diametrically opposite pairs, as clearly shown in Figures 1, 2 and 3. The axes of the respective protuberances thus radiate toward a common center and the 20 body A is thus virtually provided with radially positioned semi-spherical weights which mutually co-act to distribute the weight of the object so that the slightest impact imposed upon any one of the protuberances 13, such as when it contacts with the ground, compels the object to move in an uncertain, erratic or careless manner, the object tumbling over and over, and bounding first in one direction and then in another and with such uncertainty that one cannot possibly 30 determine in advance the course that the object will take after it strikes the ground.

The panel forming parts 6 may be colored in various combinations so that the object will be attractive and appealing to the eye. The toy 35 may be made in various sizes, the larger the better, of course within reasonable limits.

While I have described that the toy essentially consists of an inner rubber bladder and an outer inelastic casing, I of course do not mean 40 to be bound in this respect. The outer casing may be dispensed with entirely and the bladder formed with integral protuberances like those previously described. In this event, the resiliency of the object will be materially increased. 45 I have particularly described a form of the invention which includes said outer inelastic casing, simply for the reason that stock forms of rubber bladders (of the kind which, when inflated, take on a spherical form) may be inserted within 50 my special form of outer casing and then inflated so that diametrically disposed expanded portions thereof will be properly accommodated in the roundish protuberances of said casing.

When the toy includes an inner bladder, I 55

preferably weight same at a point diametrically opposite the inflating tube 11. The weight may be in the form of a small section of rubber 14 vulcanized to the inner walls of the bladder as shown in Figure 2. This counteracts the weight of the laced flaps 12 of the outer casing and destroys the tendency of the object to roll over onto the inflating tube side of the object.

5 I claim:

- 10 1. A cover for inflatable elastic bodies comprising a plurality of panels of flexible material, each consisting of two parts cut to provide three equi-distantly related dome-shaped projections, the marginal edges of each of which are secured 15 to the corresponding edges of like parts and are

co-operable therewith to provide the cover with a plurality of external semi-spherical protuberances.

2. A toy comprising a flexible inelastic cover characterized by semi-spherical hollow protuberances having the external surface of each one thereof faired into the external surfaces of the next adjacent ones of said protuberances and said protuberances being disposed in diametrically opposite pairs; and an inflatable spherical 10 bladder insertable in and removable from the cover and of a size to enable portions thereof to be expanded into the protuberances to entirely fill same.
